UNITED STATES PATENT OFFICE.

WILLIAM H. WOOD, OF ROCHESTER, NEW YORK.

MEANS FOR ATTACHING BUTTONS.

SPECIFICATION forming part of Letters Patent No. 291,562, dated January 8, 1884.

Application filed March 5, 1883. (No model.)

To all whom it may concern:

Be it known that I, WILLIAM H. WOOD, of Rochester, Monroe county, New York, have invented a certain new and useful Improvement in Means for Attaching Buttons to Leather and Fabrics; and I do hereby declare that the following is a full, clear, and exact description of the same, reference being had to the accompanying drawings, in which—

10 Figure 1 is a front elevation of a machine showing my invention. Fig. 2 is an edge elevation of the same. Fig. 3 is a rear elevation. Fig. 4 is a vertical section through the jaws in line $x x$ of Fig. 1, on an enlarged scale. Fig. 5 is a plan of a portion of the lower jaw. Fig. 6 is a front elevation of a portion of the two jaws, showing the notches therein. Fig. 7 is a modification showing the head of a pair of pinchers with my improvement. Fig. 8 is a cross-section of the jaws of the pinchers in line $y y$ of Fig. 7, enlarged. Fig. 9 is a view of the fastening.

15 My improvement relates to means for securing buttons to leather and fabrics, and is designed to be used in connection with the button-fastening for which I applied for patent November 11, 1882.

20 The invention consists of jaws of peculiar construction, as hereinafter described, and also of a presser acting in combination therewith, as will be more fully set forth.

25 In the drawings, A shows a frame bolted to a table, B, and having vertical ways C C, in which slides a gate, D. The bottom of the gate is pivoted at a to a lever, E, having its fulcrum at b , and provided at its long end with a connecting-rod, c, which connects with a treadle on the floor. (Not shown in the drawings.) A spring, D', may connect the base A 30 and the lever E, or other equivalent arrangement employed to keep the gate always elevated, except when drawn down by the lever.

35 G G' are two jaws attached, respectively, to the main frame and the gate. The outer faces of the jaws consist of thin edges $d d$, which rest in the same plane, and in these edges are made coincident notches $f f$, Fig. 6, of sufficient depth to receive the two sides of the button-fastening shown in Fig. 9. In the jaws, 40 back of the notches, are made half-circular cavities $l l$, of sufficient size to receive the

button and to hold it in a straight position while the jaws are closing upon the sides of the fastening.

The button-fastening, as shown in Fig. 9, 45 consists of a base, h , and an open hook, i , having a projecting outturned extremity, k . The hook is first inserted through a puncture made in the leather; the button is then placed thereon; and the object of my present invention is to close the two sides of the hook together into the form shown in Fig. 4, at the same time setting the projecting end of the hook down flatwise upon the leather, and 50 clamping the latter firmly between the projecting end on one side and the base of the fastening on the other side. A series of the fastenings having been attached to the leather, 55 they are passed one after another to the jaws. Each hook is placed in the notch of the lower jaw, the hook standing upright and the leather resting against the face of the jaw. The button, which projects beyond, rests in the cavity l , and is thereby retained in a straight position. The upper jaw is then brought down, 60 its notch striking the upper half of the hook, and as the two jaws come together the two sides of the hook are compressed, bringing 65 them near together and forming an eye to hold the button, at the same time setting the projecting end k down flatwise upon the leather, and firmly clamping it against the base of the fastening on the opposite side. The thin edges 70 of the jaws clamp the sides of the hook and force them near together, the notches receive 75 the sides, and the cavity in the back of the jaws holds the button. The notches form 80 a gage to prevent the sides of the hook from being closed so closely as to be cut off by the jaws or injured by the contact, which would 85 be the case if the jaws closed directly on them when heavy pressure was applied.

The apparatus above described is intended 90 for use in shops and stores where constant work is done. The invention is equally adapted 95 to hand instruments, of which one form is shown in Fig. 7, the same being a pair of ordinary nippers, except that the jaws are provided with the notches f and cavity l . The jaws are placed around the hook and closed together 100 in the manner before described. Other forms of instruments may be used in a similar man-

ner. I do not wish to confine myself to any peculiar form of the machine or instrument, but to embody any form which has the jaws constructed as before described.

5 Where large machines are used, such as shown in Figs. 1 and 2, I employ a gage or presser for holding up against the base of the fastening while the jaws close, constructed and arranged as follows: H is a bow or arch, pivoted at *m m* to the sides of the frame, and extending up over the frame. In the sides are made inclined slots *n n*, Fig. 2, through which pass screws or pins *p p*, attached to the reciprocating gate D. It will be seen that when 15 the gate moves down the screws sliding in the slots will move the arch back, and when the gate rises they will move it forward.

I is an arm of the arch, which curves downward in the rear of the machine. r is a screw, 20 which screws horizontally through the lower end of the arm, and has on its inner end a flat head, s, which forms the presser, the same coming opposite the notch in the lower jaw. u is a nut on the screw, clamping against the 25 arm to secure the gage or presser at any adjustment. When the jaws close to compress the hook, the presser is brought up firmly against the base of the button-fastening and resists any tendency of the fastening to move out 30 away from the jaws. When the jaws open to release the hook, the presser also moves back out of the way and allows the leather to be moved up to bring another fastening in posi-

tion. Where hand instruments are used, the presser is not required, as the finger of the 35 operator holds the leather up to the work.

This invention is intended more particularly 40 for fastening buttons on shoes, but is also adapted to other uses where buttons are to be applied to leather or fabrics.

Having described my invention, what I 45 claim as new, and desire to secure by Letters Patent, is—

1. The combination, substantially as shown and described, of the jaws G G', movable with 45 relation one to another, and provided with the thin edges d d, notched at f f, to properly clamp the button-fastening, and also provided with the cavities l l, adjacent to said edges, and at the front of said jaws to receive the 50 button, as set forth.

2. In an apparatus for attaching buttons, the combination, with jaws which close together to compress the sides of the fastening, of a presser or gage, substantially as described, 55 and mechanism to move the same automatically forward to press against the base of the fastening while the jaws are closing, as herein shown and set forth.

In witness whereof I have hereunto signed 60 my name in the presence of two subscribing witnesses.

W. H. WOOD.
